UNITED STATES PATENT OFFICE.

CLARENCE O. FLOWERS, OF READING, PENNSYLVANIA, ASSIGNOR TO ROBERTS AND SCHAEFER COMPANY, OF CHICAGO, ILLINOIS, A CORPORATION OF ILLINOIS.

MEASURING FEEDER.

Application filed December 31, 1927. Serial No. 243,788.

My invention relates to improvements in measuring feeders and has for one object to provide a new and improved type of feeder wherein the driving and working connection 5 between the skip and bucket and feeder and gate are simplified. Another object is to provide a device wherein the bucket itself is independent of the counterweight and operates the loading gate. Another object 10 is to provide a compact, simple and durable equipment for measuring and feeding coal and the like. Other objects will appear from time to time throughout the specification and claims.

15 My invention is illustrated more or less diagrammatically in the accompanying drawings, wherein—

Figure 1 is a vertical section;

20 Figure 2 is a section along the line 2—2 of Figure 1;

Figure 3 is a section along the line 3—3 of Figure 1;

Figure 4 is a vertical section showing the parts in different positions.

25 Like parts are indicated by like characters throughout the specification and drawings.

I have illustrated my invention in connection with a mixing and handling apparatus 30 such as is illustrated in Ross Patent No. 1,577,365 though it will be evident that my invention might be equally well applied where but a single feeder loads into a bucket.

A A¹ are bins adapted to contain coal or 35 similar finely divided material. They are spaced apart, there being sufficient room between them for a skip or bucket elevator which travels along vertical tracks A² A², the bucket being indicated at A³. A⁴ is a 40 hoisting cable to raise and lower the bucket. The bucket is open at the top and has a discharge door A⁵ at the bottom which door is held closed by a roller A⁶ traveling along a roller track A⁷. The means for dumping 45 the load from the bucket at the top of its excursion at the end of the track A⁷ forming no part of my invention and not here illustrated or described. The bins A A¹ are similar except that they are reversed so that 50 each one of them discharges inwardly toward the end of the bucket. A description of one will therefore suffice for both.

Each of the bins A A¹ has an inclined 55 bottom floor B discharging through a port B¹ into a measuring hopper B². B² is an

adjustment plate adapted to drop down by gravity across the throat B¹. This gate is suspended by chains B⁴ passing over a sheave B⁵ and wound about a shaft B⁶ controlled by a hand wheel B⁷ whereby the 60 operator may manually control the effective opening of the discharge throat from each of the hoppers, which opening under normal conditions will be set and allowed to remain without adjustment.

65 C is a flat gate pivoted on the bottom of the measuring hopper B². When in the discharge position it extends as a continuation of the downwardly inclined floor of the hopper B² to permit discharge from the measuring hopper into the bucket. C¹ is a bracket on the bucket provided with a roller

70 C², which roller may engage the underside of the gate C to raise it from a position where it prolongs the bottom of the measuring hopper into the closed position as indicated to close the hopper. This takes place when the bucket travels up on its upward excursion. The gate C when in the closed position is held shut by a latch C³ which will not be described in detail as it forms no part of the invention. Thus when the bucket is 75 in the down position the measuring hopper is free to discharge into it and when it is in the upper position the measuring hopper 80 will be closed to prevent discharge of material from the measuring hopper into the bucket shaft in the absence of the bucket.

D is an undercut gate pivoted at D¹ and 85 adapted to work back and forth across the throat B¹. This undercut gate has side flanges D² between which extends a brace member D³. Extending forwardly from this brace member is an operating nose D⁴ which nose is in line with the bucket roller 90 C² so that as the bucket comes up, it will engage this nose and move it from the outwardly projecting position where the undercut gate is closed back up out of line with the bucket to open the undercut gate. The 95 inertia of this gate in its movement imparted by the bucket is sufficient to swing it up far enough so that it will remain out of line with the bucket and not interfere with it upon its return travel. D⁵ D⁶ are cables extending from the member D³ about sheaves D⁶ then downwardly along the path of the bucket to the cross member D⁷, which cross member may be engaged by the bucket bottom 100 as it descends to pull on these cables and 105

110

close the undercut gate after the bucket has gone down far enough to open the discharge gate from the measuring hopper. Thus the bucket itself directly opens and closes both 5 the undercut gate to control the flow into the measuring hopper and the flap gate to prevent flow from the measuring hopper.

Pivoted on the cross member D³ is an adjusting plate E. This plate is curved and 10 extends down behind the undercut gate but slightly above it. E¹ are adjusting bars pivoted on the free end of the gate slideable in the sleeve E² on the gate flap D² and adapted to be held in place by a set screw E³. 15 Adjustment marks are placed on this arm to indicate the position it and the member E must assume to control the volume of flow through the undercut gate and limit the amount of material that passes into the 20 measuring hopper, this being important especially in connection with a device where two measuring hoppers are used both feeding to a single bucket for the purpose of mixing different materials as they are fed 25 to the bucket. Obviously the distance between the plate E and the undercut gate D controls the amount of material which may 30 flow into the measuring hopper and hence by manipulation of the two members E in connection with the two measuring hoppers, the operator can control the relative amount 35 of different types of material fed simultaneously to the bucket.

I claim:

35 1. In combination a single hoisting bucket, a bin adapted to discharge material thereinto when it is at the lower end of its excursion, a measuring hopper fixed in position and interposed between the bin and the 40 bucket, an undercut gate adapted to control the flow of the material from the bin to the measuring hopper, a second gate adapted to control the flow of material from the hopper to the bucket, means associated with

the single bucket only for opening and closing both gates. 45

2. In combination a hoisting bucket, a bin adapted to discharge material thereinto when it is at the lower end of its excursion, a measuring hopper fixed in position and interposed between the bin and the bucket, an undercut gate pivoted intermediate the bin and the bucket and adapted to control the flow of the material from the bin to the measuring hopper, a second gate adapted to control the flow of material from the hopper to the bucket, means associated with the bucket only for opening and closing both gates, a member fixed on and projecting forwardly from the undercut gate into the path 50 of the bucket and adapted to be contacted by the bucket as it starts up, to open the gate. 55

3. In combination a hoisting bucket, a bin adapted to discharge material thereinto when it is at the lower end of its excursion, a measuring hopper fixed in position and interposed between the bin and the bucket, an undercut gate pivoted intermediate the bin and the bucket and adapted to control the flow of the material from the bin to the 60 measuring hopper, a second gate adapted to control the flow of material from the hopper to the bucket, means associated with the bucket only for opening and closing both 65 gates, a member fixed on and projecting forwardly from the undercut gate into the path 70 of the bucket and adapted to be contacted by the bucket as it starts up, to open the gate. 75

Signed at Worth, county of McDowell and State of West Virginia, this 19th day of December, 1927. 80 85

CLARENCE O. FLOWERS.
